United States Patent Office.

HENRY H. BARSTOW, OF CHICAGO, ILLINOIS.

Letters Patent No. 80,116, dated July 21, 1868.

IMPROVED NUTMEG-GRATER.

The Schedule referred to in these Letters Patent and making part of the same.

TO ALL WHOM IT MAY CONCERN:

Be it known that I, HENRY H. BARSTOW, of Chicago, in the county of Cook, and State of Illinois, have invented a new and improved Grater for Abrading Nutmegs and other substances; and I do hereby declare that the following is a full, clear, and exact description thereof, which will enable others skilled in the art to make and use the same, reference being had to the accompanying drawings, forming part of this specification.

Figure 1 is a top view of my improved nutmeg-grater, with a removed section showing the interior parts.

Figure 2 is a section of the same through the line $z z$, fig. 1.

Similar letters of reference indicate corresponding parts.

This invention consists in placing the grater, A, within a case, B, and supporting the said grater upon and secured to any suitable springs, b, as shown. These springs rest on and are secured to the bottom of the case, as shown, and may be of any suitable form, as a straight or coiled spring, or they may be of rubber.

In practice, two springs, as shown, are preferable, but more may be employed, if desired, or the grater may be hinged at one end, and the opposite end provided with a yielding spring-action.

The nutmeg or other substance to be grated is attached to the end of a wire or stem, m, which is secured to a handle, D, as shown, the said wire passing through a vertical slot, d, in the case B. A hinged lid, H, completes the case, and prevents the escape of the grated particles, and also provides a surface against which the nutmeg is made to impinge by the action of the springs b. But this lid may be dispensed with, for, by pressing the nutmeg down upon the grater, the abrasion of the former may be produced without permitting it to come in contact with the said lid.

A horizontal opening or slot, n, as shown, at the end of the case, permits the discharge of the grated particles.

This invention provides a simple and effective household-implement, and is more easily operated than those heretofore used.

It is simple, small cost, and not liable to get out of repair.

I claim as new, and desire to secure by Letters Patent—

1. Supporting an abrading or grating-plate, A, upon one or more springs, b, substantially as shown and described, in combination with the case B, as and for the purpose set forth.

2. The stem or wire m, or other equivalent device, for holding the nutmeg or article to be grated, substantially as shown and described, in combination with grater A, springs b, all as and for the purpose set forth.

HENRY H. BARSTOW.
